204,859

HOLDER FOR LIPSTICKS AND THE LIKE

Robert A. O'Neil, Pittsburgh, Pa., assignor to Fesco, Inc., New York, N.Y., a corporation of Delaware

Filed July 8, 1965, Ser. No. 86,083

Term of patent 14 years

(Cl. D86—10)

FIG. 1.

FIG. 2.

FIG. 3.

I claim:

The ornamental design for a holder for lipsticks and the like, as shown.
